(57) **CLAIM**

The ornamental design for a transparent tube holder assembly with internal and external ribs, as shown and described.

DESCRIPTION

FIG. 1 is a generally top-directed perspective view of a transparent tube holder assembly with internal and external ribs in accordance with an embodiment of the present invention;

FIG. 2 is a generally bottom-directed perspective view of the transparent tube holder assembly of FIG. 1;

FIG. 3 is a top view of the transparent tube holder assembly with internal and external ribs of FIG. 1;

FIG. 4 is a front view of the transparent tube holder assembly with internal and external ribs of FIG. 1;

FIG. 5 is a left side view of the transparent tube holder assembly with internal and external ribs of FIG. 1;

FIG. 6 is a right side view of the transparent tube holder assembly with internal and external ribs of FIG. 1;

FIG. 7 is a bottom view of the transparent tube holder assembly with internal and external ribs of FIG. 1; and,

FIG. 8 is a rear view of the transparent tube holder assembly with internal and external ribs of FIG. 1.

The broken lines in the drawing views are included for the purpose of illustrating portions of the tube holder assembly with octagonal proximal flange that form no part of the claimed design.
